CLAIM

The ornamental design for a weight holder frame, as shown and described.

DESCRIPTION

FIG. 1 is a front perspective view of a weight holder frame, showing my new design;

FIG. 2 is a rear perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is a front perspective view of the weight holder frame, indicating the usage environment. The broken lines in FIG. 9 are directed to environment only, which form no part of the claim design.
